UNITED STATES PATENT OFFICE

WILLIAM RABKIN, OF NEW YORK, N. Y.

COIN-SLOT GUARD

Application filed August 13, 1928. Serial No. 299,263.

This invention is a guard for entrance slots and is intended primarily for use in connection with the coin tubes of coin-controlled machines but it may without substantial structural changes be employed as a guard for keyholes and other structures in which an operating element is to be inserted through an entrance opening to reach and actuate other parts. Owners of coin-controlled machines are subjected to great annoyance by mischievous or evil disposed persons inserting in the coin slots paper, chewing gum or other material which choke the coin slots and prevent the use of the machines until after the obstructions have been removed. In many instances, it is necessary to dismantle the machine in order to remove the obstructions, thereby incurring considerable expense as well as losing the use of the machine while the necessary repairs are being made. It is the object of my invention to provide a simple and inexpensive mechanism which will effectually close the coin slot against the entrance of paper or other material which is apt to choke the slot so that the slot will always be in condition to admit a coin, and a further object of the invention is to provide a coin guard which upon the entrance of a coin will operate to propel the coin into and through the coin tube or chute. One embodiment of the invention is illustrated in the accompanying drawing and will be hereinafter fully described, the novel features being particularly pointed out in the appended claims.

In the drawing:

Figure 1 is a vertical section of a portion of a coin tube and the frame of a coin-controlled machine having my invention applied thereto;

Fig. 2 is a plan view of the coin tube with a part of the frame in section on the line 2-2 of Fig. 1;

Fig. 3 is a view similar to Fig. 2 but showing the guard in the position assumed when a coin is inserted through the coin slot;

Fig. 4 is a transverse section on the line 4-4 of Fig. 2, and

Fig. 5 is a transverse section on the line 5-5 of Fig. 2.

The reference numeral 1 indicates a portion

of the frame of a coin-controlled machine which is shown as having an opening 2 in its wall and a plate 3 secured over the opening and provided with a coin slot 4, the plate 3 being usually employed as a name plate and containing inscriptions descriptive of the machine and directions for its operation. The use of the plate 3, however, is merely a matter of convenience and the coin slot may be formed in the wall of the machine frame as is obvious.

The coin chute is so arranged that its coin-receiving end is disposed in juxtaposition to the coin slot 4 and of such form as to receive the coin as it passes through the coin slot. In the present instance, the coin tube or chute comprises an upper plate 5 having its inner or rear end turned downwardly, as shown at 6, to direct the coin to the operating mechanism, and a lower plate 7 which at its front end is provided with a depending flange 8 whereby it may be secured by screws or other fasteners to the plate 3 or the frame of the machine immediately at the coin slot 4 and flush with the lower wall of said slot. Side flanges 9 are also formed on the lower plate 7 to abut the upper plate 5 and thereby properly space the plates as well as form guides to prevent lateral movement of the coin and insure its travel to the working mechanism. The upper and lower plates are, of course, firmly connected so as to maintain their desired relation, and, in the present instance, the connecting means consist of two screws 10 inserted through the upper plate and having threaded engagement with the lower plate and also passing through and securing a keeper 11 upon the upper plate, said keeper consisting of a light bar having bosses 12 at its ends on its under side to rest upon the upper plate and thereby space the keeper from said plate, as shown. This keeper may conveniently be formed of sheet metal having its ends doubled upon itself to provide the spacing bosses, as shown clearly in Fig. 5. It will be noted that the front edge of the upper plate 5 is spaced from the plate 3 on the front wall of the machine frame or casing but a central tongue 13 is formed on said plate to project across the space between its

edge and the coin slot above the slot and thereby prevent the coin being inserted through the slot in such position that it will not enter the coin chute. Pivots mounted at their rear ends in openings 14 provided therefor in the upper plate 5 are jaws 15 having rearwardly projecting shanks or stems 16 formed with down-turned tenons 17 engaged through the openings 14 so as to constitute pivots for the jaws. The inner opposed edges of the jaws and the stems or shanks are straight and normally lie parallel, as shown clearly in Fig. 2, and at their forward ends the jaws are formed with depending lips 18 which terminate close to the lower plate 7 of the coin chute, as shown clearly in Fig. 1, and are of such lateral extent that one end thereof is behind the plate or frame beyond the end of the coin slot while the opposite or inner end thereof is disposed between the ends of the coin slot, the lips consequently serving as guards to prevent the entrance of paper or the like into the coin chute through the ends of the coin slot. The depending lips 18 terminate short of the inner edges of the respective jaws which are stepped, as shown at 19, and at the transverse side of each step 19 is a second depending lip 20 which is disposed at a greater distance from the coin slot than is the respectively adjacent lip 18 and each lip 20 has its inner edge or end extended inwardly beyond the inner straight edge of the respective jaw, as shown at 21, whereby to meet on the medial line of the coin chute under the tongue 13 so that when the parts are in normal position the guard will extend through the entire extent of the slot.

When a coin, indicated at 22, is inserted through the coin slot 4, the edge of the coin will impinge against the inner opposed edges of the lips 18 and by reason of its curvature will pass between the said lips so that the pressure exerted upon the coin to pass it through the coin slot will tend to spread the lips and open the jaws. Obviously, this opening movement effected by engagement of the coin with the lips 18 will be comparatively slight but as the entrance of the coin continues its edge will engage the opposed ends 50 of the lips 20 and will fully open the jaws so that the coin may pass into the coin chute. The jaws are normally held in their closed position and caused to yieldably resist the entrance of the coin by a spring 23 which, in 55 the form shown, rests upon the upper plate 5 of the coin chute and has its ends passing under the keeper 11 to bear against the outer sides of the stems 16 of the jaws. When the jaws are opened through the engagement therewith of an inserted coin, the ends of the 60 spring will be spread and the spring thereby put under increased tension. As soon as that diameter of the coin which is substantially parallel with the plate 3 or the frame of the machine casing clears the projecting ends 21

of the lips 20, the spring will contract and close the jaws and this action will cause the ends 21 of the lips 20 to ride upon the edge of the coin with such force that the coin will be forcibly driven through the coin chute and must pass to the operating mechanism. The lips 20 are preferably beveled on their rear sides so that they will not bind or bite on the edge of the coin.

The jaws will yield readily to an inserted coin but will effectually resist the entrance of paper or gum or other material which is lacking in rigidity and, consequently, such material cannot be passed through the coin slot into the coin chute but will remain in the slot and it may be easily removed from the coin slot without requiring a dismantling of the entire apparatus. The device is very simple and may be produced and applied to any machine at a very low cost and it occupies very little space so that it will not interfere in any way with the usual arrangement and operation of the mechanism of the coin-controlled machine.

Having thus described the invention, I claim:

1. The combination of a coin chute, and an element covering the entrance end of the coin chute and provided with a coin slot, one wall of the coin chute being spaced from said element and having a tongue projecting to the element at the side of the coin slot therein, a pair of jaws mounted upon the said wall of the coin chute and movable toward and from each other and provided adjacent the coin slot with elements covering the slot at the exit side thereof, and means for yieldably holding the jaws together.

2. The combination with a coin chute, and an element covering the end of the chute and provided with a coin slot, of jaws mounted on the exterior of the chute and provided at their free ends with lips depending at right angles to the horizontal plane of the jaws between the end of the chute and said covering element and adapted to cover the coin slot in said element at the exit side of the slot, and means for yieldably holding the jaws to each other.

3. The combination of a coin chute, an element covering the end of the coin chute and provided with a coin slot, jaws mounted externally upon the coin chute and movable toward and from each other and provided at their free ends with depending lips between the covering element and the end of the chute arranged in stepped relation whereby they will bridge the coin slot in position to be engaged successively by a coin inserted through the slot and thereby separated, and resilient means bearing upon the jaws and tending constantly to move them toward each other whereby to propel an inserted coin into the coin chute as the coin clears the inner lips.

4. The combination of a coin chute com-

prising upper and lower plates, the upper plate terminating short of the lower plate, means for securing said plates in spaced relation, an element covering the end of the coin chute and provided with a coin slot registering with the end of the chute, jaws pivotally mounted externally upon the upper plate of the coin chute and provided at their free ends with depending lips between the covering element and the end of the plate and bridging the slot in said covering element to be engaged by an inserted coin and thereby separated, a keeper secured on the upper plate of the coin chute and bridging the jaws, and a bow spring resting upon the upper plate of the coin chute with its ends bearing against the outer sides of the jaws and disposed below the keeper.

In testimony whereof I affix my signature.

20 WILLIAM RABKIN. [L.S.]
